UNITED STATES PATENT OFFICE

127,475

DESIGN FOR AN ELECTRIC LIGHT FIXTURE

Samuel G. House, Miami, Fla., assignor to Robert
J. Boone, Miami, Fla.

Application January 31, 1941, Serial No. 98,629

Term of patent 14 years

To all whom it may concern:

Be it known that I, Samuel G. House, a citizen of the United States and a resident of Miami, in the county of Dade and State of Florida, have invented the new, original, and ornamental Design for an Electric Light Fixture, of which the following is a specification, reference is had to the accompanying drawing, forming part thereof, in which:

Figure 1 is a view in perspective of an electric light fixture, showing my new design.

Figure 2 is a top plan view of the same.

Figure 3 is a bottom plan view.

Figure 4 is an end view in perspective of an electric light fixture.

The supporting chains, canopy and wire shown in Fig. 1 are omitted from Figs. 2, 3 and 4 for convenience of illustration.

The dominant features of my design reside in the portions shown in full lines.

I claim:

The ornamental design for an electric light fixture, as shown and described.

SAMUEL G. HOUSE.
